INVENTOR:

George Henry Barsante
By Chas. H. Luther
ATTORNEY:

UNITED STATES PATENT OFFICE.

GEORGE HENRY BARSANTEE, OF PROVIDENCE, RHODE ISLAND, ASSIGNOR TO GEORGE W. DOVER, INCORPORATED, OF PROVIDENCE, RHODE ISLAND, A CORPORATION OF RHODE ISLAND.

SAFETY-CATCH FOR BROOCHES AND THE LIKE.

1,315,273.

Specification of Letters Patent.

Patented Sept. 9, 1919.

Application filed May 20, 1919. Serial No. 298,391.

To all whom it may concern:

Be it known that I, GEORGE HENRY BARSANTEE, a citizen of the United States, residing at Providence, in the county of Providence and State of Rhode Island, have invented a new and useful Improvement in Safety-Catches for Brooches and the like, of which the following is a specification.

In the usual construction of safety catches for brooches and the like, in which the movable fastening member straddles the keeper or relatively stationary member, there is nothing to prevent the movable fastening member from spreading and separating from the keeper, thereby ruining the utility of the catch. This spreading and loss of the movable or fastening member is of common occurrence in this form of catch, as the movable fastening member is necessarily small and delicate in construction.

The object of my invention is to improve the construction of a safety catch for brooches and the like, whereby spreading and loss of the movable fastening member of the catch is prevented and the catch as a whole greatly improved in construction and operation.

A further object of my invention is to construct such a safety catch so that the pin-tongue opening is at the top of the catch, whereby the movable fastening member, which straddles the keeper, may be rotated in either direction to fasten the pin-tongue in the catch.

My invention consists in the peculiar and novel construction of a safety catch for brooches and the like, whereby the movable or fastening member is locked against spreading or separating from the keeper, said safety catch having details of construction, as will be more fully set forth herein-after and claimed.

Figure 1 is an end view of a brooch provided with my improved safety catch, showing the catch in the open position.

Fig. 2 is a view similar to Fig. 1 showing the catch closed with the movable fastening member to the right in full lines and to the left in broken lines.

Fig. 3 is a sectional view of the safety catch end of the brooch taken on line 3.3 of Fig. 2 with the catch closed and the pin-tongue fastened in the catch.

Fig. 4 is a plan view of the blank from

which the movable fastening member is formed.

Fig. 5 is a longitudinal sectional view through the blank taken on line 5.5 of Fig. 4, and

Fig. 6 is a front view, Fig. 7 an edge view and Fig. 8 a back view of the keeper.

In the drawing 9 indicates the body of a brooch or similar article of jewelry, 10 a pin-tongue and 11 my improved safety catch which consists essentially of a relatively stationary keeper 12 and a movable fastening member 13.

The body of the keeper 12 is circular in form and has a central outwardly extending pin-tongue opening 14, a central approximately round boss 15 on its front, a corresponding recess 16 in its back and a base 17 extending front and back, with oppositely disposed upwardly extending locking members 18.18 as shown in Fig. 3.

The fastening member 13 is first blanked out as shown in Figs. 4 and 5 and then bent U shaped. It straddles the keeper 12 and has a ring shaped front member 19, which lies flat against the front of the keeper 12 over the boss 15, an open back member 20 which lies flat against the keeper 12 and which has a boss 21 which enters the recess 16 in the back of the keeper 12 and two angular outwardly extending operating members 22.22 connected with the back and front members and which form an outwardly extending central pin-tongue opening 23. The locking members 18.18 extend upward and over the front member 19 and back member 20, as shown in Fig. 3 and lock the fastening member against spreading or separating from the keeper.

The locking members 18.18 are formed by splitting the base centrally. If preferred the keeper and fastening member may be supplied separate to the trade as jewelers' findings with the locking members 18.18 partly bent up as shown in full lines in Fig. 7. The base 17 is then soldered to the back of the brooch or similar article, the fastening member snapped over the keeper and the locking members then bent up into place, as shown in Fig. 3.

When in use the fastening member 13 is turned so as to bring its pin-tongue opening 23 into alignment with the pin-tongue opening 14 in the keeper 12, and the pin-tongue

- 10 depressed into the keeper, as shown in full lines in Fig. 1. The fastening member 13 is then turned, in either direction, by the operating members 22, to its limit, thereby 5 fastening the pin-tongue in the catch, as shown in Figs. 2 and 3, by the front and back of the fastening member extending over and closing the pin-tongue opening in the keeper.
- 10 By this construction the pin-tongue opening is in a central position, the fastening member may be turned in either direction to fasten the pin-tongue in the catch and the heretofore free front and back members 15 of the fastening member are securely locked in place, thereby preventing spreading or separating of the fastening member from the keeper.

Having thus described my invention, I 20 claim as new.

1. A safety catch for brooches and the like, comprising a keeper having a base member and a circular body member having a pin-tongue opening, a fastening member 25 having coinciding circular front and back members straddling the body of the keeper and in which are pin-tongue openings which coincide with the pin-tongue opening in the keeper, when the catch is open, operating

members connecting the front and back 30 members of the fastening member, means for rotatably securing the fastening member to the body of the keeper, and means on the keeper engaging with the front and back members of the fastening member, to lock 35 the fastening member to the keeper.

2. A safety catch for brooches and the like, comprising a keeper having a circular body member with a central pin-tongue opening, a boss on its face and a correspond- 40 ing recess in its back and a base with oppo- sitely disposed upwardly extending locking members, a U-shaped fastening member straddling the body member of the keeper and having a ring shaped front over the boss 45 on the keeper, an open back member which has a boss in the recess in the keeper and two angular outwardly extending operating members connecting the front and back members and which form a central pin- 50 tongue opening, when the catch is open, said locking members on the base of the keeper extending over the front and back members of the fastening member, to lock the fastening member to the keeper, as described. 55

In testimony whereof, I have signed my name to this specification.

GEORGE HENRY BARSANTEE.
